(57) **CLAIM**

The ornamental design for a display screen or portion thereof with graphical user interface, as shown and described.

DESCRIPTION

The patent or application file contains at least one drawing executed in color. Copies of this patent or patent application publication with color drawing(s) will be provided by the Office upon request and payment of the necessary fee.

FIG. 1.1 is a front view of a first image in a sequence of a display screen or portion thereof with graphical user interface showing our new design;

FIG. 1.2 is a front view of a second image in the sequence thereof;

FIG. 1.3 is a front view of a third image in the sequence thereof;

FIG. 1.4 is a front view of a fourth image in the sequence thereof;

FIG. 1.5 is a front view of a fifth image in the sequence thereof;

FIG. 1.6 is a front view of a sixth image in the sequence thereof;
FIG. 1.7 is a front view of a seventh image in the sequence thereof;
FIG. 1.8 is a front view of an eighth image in the sequence thereof;
FIG. 1.9 is a front view of a ninth image in the sequence thereof;
FIG. 1.10 is a front view of a tenth image in the sequence thereof;
FIG. 1.11 is a front view of an eleventh image in the sequence thereof;
FIG. 1.12 is a front view of a twelfth image in the sequence thereof;
FIG. 1.13 is a front view of a thirteenth image in the sequence thereof;
FIG. 1.14 is a front view of a fourteenth image in the sequence thereof;
FIG. 1.15 is a front view of a fifteenth image in the sequence thereof;
FIG. 1.16 is a front view of a sixteenth image in the sequence thereof;
FIG. 1.17 is a front view of a seventeenth image in the sequence thereof;
FIG. 1.18 is a front view of an eighteenth image in the sequence thereof;
FIG. 1.19 is a front view of a nineteenth image in the sequence thereof;
FIG. 1.20 is a front view of a twentieth image in the sequence thereof;
FIG. 1.21 is a front view of a twenty-first image in the sequence thereof;
FIG. 1.22 is a front view of a twenty-second image in the sequence thereof;
FIG. 1.23 is a front view of a twenty-third image in the sequence thereof;
FIG. 1.24 is a front view of a twenty-fourth image in the sequence thereof;
FIG. 1.25 is a front view of a twenty-fifth image in the sequence thereof;
FIG. 1.26 is a front view of a twenty-sixth image in the sequence thereof;
FIG. 1.27 is a front view of a twenty-seventh image in the sequence thereof;
FIG. 1.28 is a front view of a twenty-eighth image in the sequence thereof;
FIG. 1.29 is a front view of a twenty-ninth image in the sequence thereof;
FIG. 1.30 is a front view of a thirtieth image in the sequence thereof;
FIG. 1.31 is a front view of a thirty-first image in the sequence thereof;
FIG. 1.32 is a front view of a thirty-second image in the sequence thereof;
FIG. 1.33 is a front view of a thirty-third image in the sequence thereof;
FIG. 1.34 is a front view of a thirty-fourth image in the sequence thereof;
FIG. 1.35 is a front view of a thirty-fifth image in the sequence thereof;
FIG. 1.36 is a front view of a thirty-sixth image in the sequence thereof;

FIG. 1.37 is a front view of a thirty-seventh image in the sequence thereof;
FIG. 1.38 is a front view of a thirty-eighth image in the sequence thereof;
FIG. 1.39 is a front view of a thirty-ninth image in the sequence thereof;
FIG. 1.40 is a front view of a fortieth image in the sequence thereof;
FIG. 1.41 is a front view of a forty-first image in the sequence thereof;
FIG. 1.42 is a front view of a forty-second image in the sequence thereof;
FIG. 1.43 is a front view of a forty-third image in the sequence thereof;
FIG. 1.44 is a front view of a forty-fourth image in the sequence thereof;
FIG. 1.45 is a front view of a forty-fifth image in the sequence thereof;
FIG. 1.46 is a front view of a forty-sixth image in the sequence thereof;
FIG. 1.47 is a front view of a forty-seventh image in the sequence thereof;
FIG. 1.48 is a front view of a forty-eighth image in the sequence thereof;
FIG. 1.49 is a front view of a forty-ninth image in the sequence thereof;
FIG. 1.50 is a front view of a fiftieth image in the sequence thereof;
FIG. 1.51 is a front view of a fifty-first image in the sequence thereof;
FIG. 1.52 is a front view of a fifty-second image in the sequence thereof;
FIG. 1.53 is a front view of a fifty-third image in the sequence thereof;
FIG. 1.54 is a front view of a fifty-fourth image in the sequence thereof;
FIG. 1.55 is a front view of a fifty-fifth image in the sequence thereof;
FIG. 1.56 is a front view of a fifty-sixth image in the sequence thereof;
FIG. 1.57 is a front view of a fifty-seventh image in the sequence thereof;
FIG. 1.58 is a front view of a fifty-eighth image in the sequence thereof;
FIG. 1.59 is a front view of a fifty-ninth image in the sequence thereof;
FIG. 1.60 is a front view of a sixtieth image in the sequence thereof;
FIG. 1.61 is a front view of a sixty-first image in the sequence thereof; and
FIG. 1.62 is a front view of a sixty-second image in the sequence thereof.
The appearance of the animated images sequentially transition between the images shown in FIGS. 1.1-1.62. The process or period in which one image transitions to another image forms no part of the claimed design.
The broken lines in the drawings illustrate the perimeter of a display screen or portion thereof and form no part of the claimed design.
